PHARMACEUTICAL COMPOSITIONS OF 6-CHLORO - 7 - SULFAMYL - 3,4 - DIHYDRO - 2H - [1,2,4] - BENZOTHIADIAZINE 1,1 - DIOXIDE AND AN INDOLE ALKALOID OF THE APOCYNACEAE FAMILY

George de Stevens and Lincoln Harvey Werner, Summit, N.J., assignors to Ciba Corporation, New York, N.Y., a corporation of Delaware

No Drawing. Original application Sept. 12, 1963, Ser. No. 308,327, now Patent No. 3,288,678, dated Nov. 29, 1966. Divided and this application Mar. 18, 1966, Ser. No. 535,357

The portion of the term of the patent subsequent to Nov. 29, 1963, has been disclaimed
7 Claims. (Cl. 167—65)

ABSTRACT OF THE DISCLOSURE

Compositions (and methods for their preparation) useful in the treatment of hypertension and containing essentially (1) 6 - chloro - 7 - sulfamyl - 3,4 - dihydro - 2H - [1,2,4] - benzothiadiazine-1,1-dioxide and (2) an indole alkaloid of the Apocynaceae family, such as reserpine.

This application is a division of application Ser. No. 308,327, filed Sept. 12, 1963, now U.S. Patent 3,288,678 issued Nov. 29, 1966 which in turn is in part a continuation of application Ser. No. 845,623, filed Oct. 12, 1959; which in turn is in part a continuation of application Ser. No. 791,831, filed Feb. 9, 1959; which in turn is in part a continuation of application Ser. No. 764,482, filed Sept. 29, 1959; which in turn is in part a continuation of application Ser. No. 751,620, filed July 29, 1959; which in turn is in part a continuation of application Ser. No. 740,582, filed June 9, 1958; which in turn is in part a continuation of application Ser. No. 727,242, filed Apr. 9, 1958; which in turn is in part a continuation of application Ser. No. 718,452, filed Mar. 3, 1958 all of which are now abandoned.

This invention relates to and has for its object the provision of compositions (and methods for their preparation), useful in the treatment of hypertension. These compositions contain essentially (1) 6-chloro-7-sulfamyl-3,4-dihydro-2H-[1,2,4]-benzothiadiazine-1,1-dioxide and (2) an indole alkaloid of the Apocynaceae family, such as reserpine.

One may desirably use about 1 to about 20 percent of 6-chloro-7-sulfamyl-3,4-dihydro-2H-[1,2,4] - benzothiadiazine-1,1-dioxide to about 0.005 to about 0.5 percent of indole alkaloid (e.g. reserpine, deserpine or rescinnamine). Preferred proportions are about 2.5 to about 10 percent of the dihydro benzothiadiazine-1,1-dioxide to about 0.01 to about 0.04 percent of indole alkaloid (particularly about 2.5 percent benzothiadiazine-1,1-dioxide to about 0.01 percent indole alkaloid).

The tablet, capsule or pill provides a convenient oral form of administration of the compositions of the invention. These forms may be compounded to contain about 10 to about 200 mg. (more particularly about 25 to about 100 mg.) of dihydro benzothiadiazine-1,1-dioxide and about 0.05 to about 5.0 mg. (more particularly about 0.1 to about 0.4 mg.) of reserpine, deserpidine or rescinnamine. Tablets may, of course, be scored to provide for fractional dosages, if desired. Complete tablets (or capsules) containing about 0.1 mg. reserpine or deserpidine or 0.5 mg. rescinnamine and about 25 mg. dihydro benzothiadiazine-1,1-dioxide are convenient for administration and may normally be administered 1-3 times daily, but administration may vary with the needs of each particular patient and is best determined by the physician in each case.

The inert fillers and binders which are normally employed in the art of tablet (or capsule) making may be used in formulating tablets (or capsules). Examples of these materials are corn starch, lactose, stearic acid, talc, magnesium stearate, tragacanth, acacia, etc. The quantities of these ingredients may vary widely in accordance with the dictates of those skilled in the art, and depend largely upon the kind, i.e. soft or hard, and size of tablet which is required. Encapsulation may also be effected, using the same excipients as those used for tablets. At any rate, as has been indicated above, the compounding is effected in exactly the same manner as that normally employed in the art. Any compatible colors, approved and certified under the provisions of the Federal Food, Drug and Cosmetic Law, may be used for esthetic purposes or as a means of identification.

Salts of the diuretic which may be used in this invention are therapeutically useful salts with metals, particularly the alkali metal salts, such as those with sodium or potassium. Mono- or poly-salts may be formed.

The 6 - chloro - 7 - sulfamyl - 3,4 - dihydro - 2H - [1,2,4] - benzothiadiazine-1,1-dioxide used in this invention may be prepared as shown in the recited examples of co-pending application Ser. No. 764,482, of common assignment, the continuation of which is now U.S. Patent No. 3,103,645, one of which are given below:

Example A

A mixture of 2.9 g. of 5-chloro-2,4-disulfamyl-aniline in 15 ml. of anhydrous diethyleneglycol dimethylether, 0.5 ml. of an ethyl acetate solution containing 109.5 g. of hydrogen chloride per 1000 ml. and 0.33 g. (0.011 mol.) of paraformaldehyde is heated to 80-90° C. and maintained at that temperature for one hour. The resulting mixture is cooled to room temperature and concentrated to one-third of its volume under reduced pressure, diluted with water, then allowed to crystallize. The product is filtered off and recrystallized from water, to yield the desired 6-chloro-7-sulfamyl-3,4-dihydro-2H-[1,2,4]-benzothiadiazine-1,1-dioxide, M.P. 266-268° C.; yield 1.4 g.

By replacing paraformaldehyde by 0.84 g. of 1,1-dimethoxymethane and proceeding as above, the same compound is obtained.

Following are working examples, illustrative of, but in no way intended to limit the present invention. Unless otherwise indicated, all parts, wherever given in the specification, are parts by weight. All sieve sizes are U.S. Standard sieve sizes.

Example 1

	10,000 tablets
	(grams)
Material and formula:	
6 - chloro - 3,4 - dihydro - 7 - sulfamyl - 2H - 1,2,4 - benzothiadiazine - 1,1 - dioxide (hydrochlorothiazide)	150.00
Reserpine	1.00
Lactose USP	1191.50
Acacia	75.00
Talc USP	75.00
Magnesium stearate USP	7.50
50% 3A alcohol, q.s.	

Procedure for preparation.—Triturate the reserpine with 100 grams of lactose and force through a No. 50 screen. Incorporate the remainder of the lactose, the acacia and the hydrochlorothiazide. Granulate with sufficient 50% 3A alcohol. Pass the moist mass through a No. 10 screen and dry with circulating air at 110° F. until moisture content is 3 percent. Break the granules on a No. 16 screen and mix with the talc and magnesium stearate. Compress into tablets weighing 150 mg., using $\frac{3}{2}$ inch punches and dies.

Example 2

Material and formula:	10,000 tablets (grams)
6 - chloro-3,4-dihydro-7-sulfamyl-2H-1,2,4-benzothiadiazine - 1,1 - dioxide (hydrochlorothiazide)	250.00
Reserpine	2.50
Lactose USP	1165.40
Corn starch (anhydrous basis)	67.10
Stearic acid powder USP	15.00
Purified water, q.s.	10

Procedure for preparation.—Triturate the reserpine with 100 grams of lactose. Pass the mixture through a No. 50 screen and combine with the hydrochlorothiazide, 38.5 grams of dry corn starch and the remainder of the lactose. Mix thoroughly. Suspend 28.6 grams of dry corn starch in 35 ml. of purified water and add 140 ml. boiling purified water to form a paste. Granulate the mixed powders with this paste, using additional water if necessary. Pass the wet mass through a No. 8 screen and dry at 100° F. with circulating air. Break the granules on a No. 14 screen and mix with the stearic acid powder. Compress into tablets weighing 150 mg., using $\frac{1}{32}$ inch punches and dies.

Example 3

Material and formula:	10,000 tablets (grams)
6 - chloro-3,4-dihydro-7-sulfamyl-2H-1,2,4-benzothiadiazine - 1,1 - dioxide (hydrochlorothiazide)	250.00
Reserpine triturate 5%	20.60
Lactose spray dried	1123.00
Corn starch (anhydrous basis)	67.10
Silicon dioxide (Cab-O-Sil)	30.00
Magnesium stearate USP	9.00
D & C Brown No. 1	0.30
Purified water, q.s.	40
50% 3A anhydrous alcohol, q.s.	

Procedure for preparation.—Mix together the reserpine triturate 5%, the hydrochlorothiazide, silicon dioxide, magnesium stearate and 38.5 grams of dried corn starch. Dissolve the color in 35 ml. of purified water and suspend 28.6 mg. of dried corn starch in this solution. Make a paste by adding 140 ml. of purified water. Granulate the mixed powders with this paste, using sufficient 50% 3A alcohol to complete the granulation. Pass the moist mass through a No. 10 screen and dry with circulating air at 100° F. until moisture is 2 percent. Break the granules on a No. 14 screen and compress into tablets weighing 150 mg., using $\frac{1}{32}$ inch punches and dies.

Example 4

Material and formula:	10,000 tablets (grams)
6 - chloro-3,4-dihydro-7-sulfamyl-2H-1,2,4-benzothiadiazine - 1,1 - dioxide (hydrochlorothiazide)	250.00
Rescinnamine	5.00
Mannitol	667.50
Gelatin	20.00
Talc USP	50.00
Magnesium stearate USP	7.50
Purified water, q.s.	65

Procedure for preparation.—Mix the rescinnamine with 50 grams of mannitol and force the mixture through a No. 50 screen. Mix the remainder of the mannitol with the hydrochlorothiazide. Dissolve the gelatin in 130 ml. purified water, using heat. Granulate the hydrochlorothiazide-mannitol mixture with the gelatin solution. Pass the moist mass through a No. 10 screen and dry at 110°

70

F. until moisture content is less than 0.5%. Break the granules on a No. 16 screen and mix them with the talc, magnesium stearate and the rescinnamine-mannitol mixture. Compress into tablets weighing 100 mg., using $\frac{1}{32}$ inch punches and dies.

Example 5

Material and formula:	10,000 tablets (grams)
6 - chloro-3,4-dihydro-7-sulfamyl-2H-1,2,4-benzothiadiazine - 1,1 - dioxide (hydrochlorothiazide)	250.00
Rescinnamine	10.00
Mannitol	1120.00
Gelatin	30.00
Talc USP	5.00
Magnesium stearate USP	15.00
Purified water, q.s.	

Procedure for preparation.—Mix the rescinnamine with 75 grams of mannitol and force through a No. 50 screen. Combine the remainder of the mannitol with the hydrochlorothiazide. Dissolve the gelatin in 180 ml. purified water, using heat. Granulate the hydrochlorothiazide-mannitol mixture with the gelatin solution. Pass the moist mass through a No. 10 screen and dry at 110° F. with circulating air until moisture content is less than 0.5 percent. Break the granules on a No. 14 screen and mix with the talc, magnesium stearate and the rescinnamine-mannitol mixture. Compress into tablets weighing 150 mg., using $\frac{1}{32}$ inch punches and dies.

Example 6

Material and formula:	10,000 tablets (grams)
6 - chloro-3,4-dihydro-7-sulfamyl-2H-1,2,4-benzothiadiazine - 1,1 - dioxide (hydrochlorothiazide)	125.00
Rescinnamine	5.00
Mannitol	790.00
Gelatin	20.00
Talc USP	50.00
Magnesium stearate	10.00
Purified water, q.s.	

Procedure for Preparation.—Mix the rescinnamine with 50 grams of mannitol and force the mixture through a No. 50 screen. Mix the remainder of the mannitol with the hydrochlorothiazide. Dissolve the gelatin in 130 ml. purified water, using heat. Granulate the hydrochlorothiazide-mannitol mixture with the gelatin solution. Pass the moist mass through a No. 10 screen and dry at 110° F. until moisture content is less than 0.5 percent. Break the granules on a No. 16 screen and mix them with the talc, magnesium stearate and the rescinnamine-mannitol mixture. Compress into tablets weighing 100 mg., using $\frac{1}{32}$ inch punches and dies.

Example 7

Material and formula:	10,000 tablets (grams)
6 - chloro-3,4-dihydro-7-sulfamyl-2H-1,2,4-benzothiadiazine - 1,1 - dioxide (hydrochlorothiazide)	250.00
Deserpidine	5.00
Lactose spray dried	1087.50
Tragacanth USP	30.00
Corn starch	75.00
Talc USP	45.00
Magnesium stearate USP	7.50
50% 3A alcohol, q.s.	65

Procedure for preparation.—Triturate the deserpidine with 100 grams of lactose and force through a No. 50 screen. Combine with the hydrochlorothiazide, tragacanth

and the remainder of the lactose in a suitable mixer and mix for 30 minutes. Granulate the mixed powders with sufficient 50% 3A alcohol. Pass the moist mass through a No. 10 screen and dry at 100° F. with circulating air until moisture content is 3 percent. Break the granules on a No. 14 screen and mix with the corn starch, talc, and magnesium stearate. Compress into tablets weighing 150 mg., using $\frac{1}{32}$ inch punches and dies.

Example 8

Material and formula:	(grams)	10,000 tablets	10
6 - chloro-3,4-dihydro-7-sulfamyl-2H-1,2,4-benzothiadiazine - 1,1 - dioxide (hydrochlorothiazide)	250.00		5
Deserpipine	2.50		15
Lactose spray dried	1232.50		20
Magnesium stearate USP	15.00		25

Procedure for preparation.—Triturate the deserpipine with 100 grams of lactose and pass the mixture through a No. 50 screen. Combine with the hydrochlorothiazide, magnesium stearate and the remainder of the lactose in a suitable mixer and mix for 30 minutes. Compress into tablets weighing 150 mg., using $\frac{1}{32}$ inch punches and dies.

Example 9

Material and formula:	(grams)	10,000 tablets	30
6-chloro-3,4-dihydro - 7 - sulfamyl-2H-1,2,4-benzothiadiazine - 1,1 - dioxide (hydrochlorothiazide)	500.00		
Deserpipine	20.00		
Lactose USP	1580.00		
Sucrose USP	125.00		
Corn starch	125.00		
Talc USP	125.00		
Magnesium stearate USP	25.00		
Purified water, q.s.			

Procedure for preparation.—Triturate the deserpipine with 300 grams of lactose and force through a No. 50 screen. Combine this material with the hydrochlorothiazide and the remainder of the lactose. Dissolve the sucrose in 125 ml. of purified water, using heat. Granulate the mixed powders with the resultant syrup, using additional water if necessary. Pass the moist mass through a No. 8 screen and dry at 100° F. until moisture content is about 2 percent. Break the granules on a No. 12 screen and mix with the corn starch, talc and magnesium stearate. Compress into tablets weighing 250 mg., using $\frac{1}{32}$ inch punches and dies.

Example 10

Material and formula:	(grams)	10,000 tablets	55
6-chloro-3,4-dihydro-7-sulfamyl - 2H - 1,2,4-benzothiadiazine-1,1-dioxide (hydrochlorothiazide)	500.00		
Reserpine	0.50		
Lactose USP	842.00		
Acacia	75.00		
Talc USP	75.00		
Magnesium stearate USP	7.50		
50% 3A alcohol, q.s.			

Procedure for preparation.—Triturate the reserpine with 100 grams of lactose and force through a No. 50 screen. Incorporate the remainder of the lactose, the acacia and the hydrochlorothiazide. Granulate with sufficient 50% 3A alcohol. Pass the moist mass through a No. 10 screen and dry with circulating air at 110° F. until moisture content is 3 percent. Break the granules on a No. 16 screen and mix with the talc and magnesium stearate. Compress into tablets weighing 150 mg., using $\frac{1}{32}$ inch punches and dies.

Example 11

Material and formula:	(grams)	10,000 tablets
6-chloro - 3,4 - dihydro-7-sulfamyl-2H-1,2,4-benzothiadiazine-1,1-dioxide (hydrochlorothiazide)	500.00	
Reserpine	10.00	
Lactose USP	907.90	
Corn starch (anhydrous basis)	67.10	
Stearic acid powder USP	15.00	
Purified water, q.s.		

Procedure for preparation.—Triturate the reserpine with 100 grams of lactose. Pass the mixture through a No. 50 screen and combine with the hydrochlorothiazide, 38.5 grams of dry corn starch and the remainder of the lactose. Mix thoroughly. Suspend 28.6 grams of dry corn starch in 35 ml. of purified water and add 140 ml. boiling purified water to form a paste. Granulate the mixed powders with this paste, using additional water if necessary. Pass the wet mass through a No. 8 screen and dry at 100° F. with circulating air. Break the granules on a No. 14 screen and mix with the stearic acid powder. Compress into tablets weighing 150 mg., using $\frac{1}{32}$ inch punches and dies.

Example 12

Material and formula:	(grams)	10,000 tablets
6-chloro-3,4-dihydro - 7 - sulfamyl-2H-1,2,4-benzothiadiazine-1,1 - dioxide (hydrochlorothiazide)	1000.00	
Reserpine triturate 5%	20.60	
Lactose spray dried	373.00	
Corn starch (anhydrous basis)	67.10

Magnesium stearate USP	9.00	
D & C Brown No. 1	0.30	
Purified water, q.s.		
50% 3A anhydrous alcohol, q.s.		

Procedure for preparation.—Mix together the reserpine triturate 5%, the hydrochlorothiazide, silicon dioxide, magnesium stearate and 38.5 grams of dried corn starch. Dissolve the color in 35 ml. of purified water and suspend 28.6 mg. of dried corn starch in this solution. Make a paste by adding 140 ml. of purified water. Granulate the mixed powders with this paste, using sufficient 50% 3A alcohol to complete the granulation. Pass the moist mass through a No. 10 screen and dry with circulating air at 100° F. until moisture is 2 percent. Break the granules on a No. 14 screen and compress into tablets weighing 150 mg., using $\frac{1}{32}$ inch punches and dies.

Example 13

Material and formula:	(grams)	10,000 tablets
6-chloro-3,4-dihydro-7-sulfamyl - 2H - 1,2,4-benzothiadiazine-1,1-dioxide (hydrochlorothiazide)	500.00	
Rescinnamine	50.00	
Mannitol	372.50	
Gelatin	20.00	
Talc USP	50.00	
Magnesium stearate USP	7.50	
Purified water, q.s.		

Procedure for preparation.—Mix the rescinnamine with 50 grams of mannitol and force the mixture through a No. 50 screen. Mix the remainder of the mannitol with the hydrochlorothiazide. Dissolve the gelatin in 130 ml. purified water, using heat. Granulate the hydrochlorothiazide-mannitol mixture with the gelatin solution. Pass the moist mass through a No. 10 screen and dry at 110° F. until moisture content is less than 0.5 percent. Break the granules on a No. 16 screen and mix them with the talc, magnesium stearate and the rescinnamine-mannitol mix-

ture. Compress into tablets weighing 100 mg., using $\frac{1}{32}$ inch punches and dies.

Example 14

Material and formula:	10,000 tablets (grams)	5
6-chloro-3,4-dihydro - 7 - sulfamyl-2H-1,2, 4-benzothiadiazine-1,1 - dioxide (hydro- chlorothiazide)	1900.00	
Rescinnamine	25.00	
Mannitol	355.00	10
Gelatin	30.00	
Talc USP	75.00	
Magnesium stearate USP	15.00	
Purified water, q.s.		15

Procedure for preparation.—Mix the rescinnamine with 75 grams of mannitol and force through a No. 50 screen. Combine the remainder of the mannitol with the hydrochlorothiazide. Dissolve the gelatin in 180 ml. purified water, using heat. Granulate the hydrochlorothiazide-mannitol mixture with the gelatin solution. Pass the moist mass through a No. 10 screen and dry at 110° F. with circulating air until moisture content is less than 0.5 percent. Break the granules on a No. 14 screen and mix with the talc, magnesium stearate and the rescinnamine-mannitol mixture. Compress into tablets weighing 150 mg., using $\frac{1}{32}$ inch punches and dies.

Example 15

Material and formula:	10,000 tablets (grams)	30
6-chloro-3,4-dihydro-7-sulfamyl - 2H - 1,2,4- benzothiadiazine-1,1-dioxide (hydrochloro- thiazide)	250.00	
Rescinnamine	50.00	35
Mannitol	620.00	
Gelatin	20.00	
Talc USP	50.00	
Magnesium stearate USP	10.00	
Purified water, q.s.		40

Procedure for preparation.—Mix the rescinnamine with 50 grams of mannitol and force the mixture through a No. 50 screen. Mix the remainder of the mannitol with the hydrochlorothiazide. Dissolve the gelatin in 130 ml. purified water, using heat. Granulate the hydrochlorothiazide-mannitol mixture with the gelatin solution. Pass the moist mass through a No. 10 screen and dry at 100° F. until moisture content is less than 0.5 percent. Break the granules on a No. 16 screen and mix them with the talc, magnesium stearate and the rescinnamine-mannitol mixture. Compress into tablets weighing 100 mg., using $\frac{1}{32}$ inch punches and dies.

Example 16

Material and formula:	10,000 tablets (grams)	40
6-chloro-3,4-dihydro-7-sulfamyl - 2H - 1,2,4- benzothiadiazine-1,1-dioxide (hydrochloro- thiazide)	500.00	
Deserpentine	0.50	45
Lactose spray dried	842.00	
Tragacanth USP	30.00	
Corn starch	75.00	
Talc USP	45.00	
Magnesium stearate USP	7.50	
50% 3A alcohol, q.s.		55

Procedure for preparation.—Triturate the deserpentine with 100 grams of lactose and force through a No. 50 screen. Combine with the hydrochlorothiazide, tragacanth and the remainder of the lactose in a suitable mixer and mix for 30 minutes. Granulate the mixed powders with sufficient 50% 3A alcohol. Pass the moist mass through a No. 10 screen and dry at 100° F. with circulating air until moisture content is 3 percent. Break the granules on a No. 14 screen and mix with the corn starch, talc,

and magnesium stearate. Compress into tablets weighing 150 mg., using $\frac{1}{32}$ inch punches and dies.

Example 17

Material and formula:	10,000 tablets (grams)	50
6-chloro-3,4-dihydro-7-sulfamyl - 2H-1,2,4- benzothiadiazine - 1,1 - dioxide (hydro- chlorothiazide)	500.00	
Deserpentine	10.00	
Lactose USP	1580.00	
Sucrose USP	125.00	
Corn starch	125.00	
Talc USP	125.00	
Magnesium stearate USP	25.00	
Purified water, q.s.		55

Procedure for preparation.—Triturate the deserpentine with 300 grams of lactose and force through a No. 50 screen. Combine this material with the hydrochlorothiazide and the remainder of the lactose. Dissolve the sucrose in 125 ml. of purified water, using heat. Granulate the mixed powders with the resultant syrup, using additional water if necessary. Pass the moist mass through a No. 8 screen and dry at 100° F. until moisture content is about 2 percent. Break the granules on a No. 12 screen and mix with the corn starch, talc and magnesium stearate. Compress into tablets weighing 250 mg., using $\frac{1}{32}$ inch punches and dies.

Example 18

Material and formula:	10,000 tablets (grams)	50
6-chloro-3,4-dihydro-7-sulfamyl - 2H-1,2,4- benzothiadiazine - 1,1 - dioxide (hydro- chlorothiazide)	1000.00	
Deserpentine	2.50	
Lactose spray dried	482.50	
Magnesium stearate USP	15.00	

Procedure for preparation.—Triturate the deserpentine with 100 grams of lactose and pass the mixture through a No. 50 screen. Combine with the hydrochlorothiazide, magnesium stearate and the remainder of the lactose in a suitable mixer and mix for 30 minutes. Compress into tablets weighing 150 mg., using $\frac{1}{32}$ inch punches and dies.

This invention may be variously otherwise embodied within the scope of the appended claims.

What is claimed is:

1. A pharmaceutical composition, in oral dosage unit form, comprising about 1 to about 20 percent of 6-chloro-7-sulfamyl-3,4-dihydro-2 - H - [1,2,4] - benzothiadiazine-1,1-dioxide, and about 0.005 to about 0.5 percent indole alkaloid of the Apocynaceae family selected from the group consisting of reserpine, deserpentine and rescinnamine.

2. A pharmaceutical composition of claim 1 in oral dosage unit form comprising about 2.5 to about 10 percent of 6-chloro-7-sulfamyl-3,4-dihydro - 2 - H - [1,2,4] - benzothiadiazine-1,1-dioxide, and about 0.01 to about 0.4 percent alkaloid of the Apocynaceae family selected from the group consisting of reserpine, deserpentine and rescinnamine.

3. A pharmaceutical composition of claim 2, in oral dosage unit form, comprising about 2.5 percent of 6-halo-7-sulfamyl-3,4-dihydro-2 - H - [1,2,4] - benzothiadiazine-1,1-dioxide and about 0.01 percent indole alkaloid of the Apocynaceae family selected from the group consisting of reserpine, deserpentine and rescinnamine.

4. A pharmaceutical composition, in oral dosage unit form, comprising about 10 to about 200 milligrams of 6-chloro-7-sulfamyl-3,4-dihydro-2 - H - [1,2,4] - benzothiadiazine-1,1-dioxide, and about 0.05 to about 5.0 milligrams indole alkaloid of the Apocynaceae family selected from the group consisting of reserpine, deserpentine and rescinnamine.

5. A pharmaceutical composition of claim 4, in oral dosage unit form, comprising about 10 to about 200 milligrams of 6-chloro-7-sulfamyl-3,4-dihydro - 2-H - [1,2,4]-benzothiadiazine-1,1-dioxide and about 0.05 to about 5.0 milligrams indole alkaloid of the Apocynaceae family selected from the group consisting of reserpine, deserpidine and rescinnamine.

6. A pharmaceutical composition of claim 4, in oral dosage unit form, comprising about 25 to about 100 milligrams of 6-chloro-7-sulfamyl-3,4-dihydro - 2 - H-[1,2,4]-benzothiadiazine-1,1-dioxide and about 0.1 to about 0.4 milligram indole alkaloid of the Apocynaceae family selected from the group consisting of reserpine, deserpidine and rescinnamine.

7. A pharmaceutical composition of claim 4, in oral dosage unit form, comprising about 25 milligrams of 6-chloro-7-sulfamyl-3,4-dihydro-2 - H - [1,2,4] - benzothiadiazine-1,1-dioxide and about 0.1 to about 0.5 milligram indole alkaloid of the Apocynaceae family selected from the group consisting of reserpine, deserpidine and rescinnamine.
